United States Patent

Des. 241,615
Patented Sept. 28, 1976

241,615

CONNECTOR FOR SUSPENDING PANELS OR THE LIKE FROM CEILINGS

Donald G. King, 241 Dickson Park Crescent,
Mississauga, Ontario, Canada

Filed Dec. 2, 1974, Ser. No. 528,701

Term of patent 14 years

Int. Cl. D8—08

U.S. Cl. D8—235

FIG. 1

FIG. 2

FIG. 1 is a perspective view of a connector for suspending panels or the like from ceilings showing my design, taken obliquely from above; and

FIG. 2 is a perspective view of the connector of FIG. 1, taken obliquely from below.

I claim:

The ornamental design for a connector for suspending panels or the like from ceilings, as shown.
